ERICH BERNFUS, OF VIENNA, AUSTRIA

MEANS FOR FORMING THE TOP LAYER OF PACKED FRUIT

Application filed May 1, 1930, Serial No. 448,981, and in Austria May 4, 1929.

An application has been filed in Austria, May 4, 1929.

This invention relates to a method of and means for forming and orderly arranging the top layer of packed fruits, particularly dried fruits.

Heretofore when packing fruits, particularly dried fruits (prunes and the like) in boxes, the plums of the top layer, which have been flattened by hand, are placed in proper order onto the inner face of the lid of the box which is open at its bottom side and subsequently the box is filled and the floor thereof is nailed thereto.

According to the present invention the flattening and orderly arrangement of the prunes and the like by hand are dispensed with.

The essential feature of the method according to the present invention consists in orderly arranging the fruits of the top layer in depressions of a plate, placing over plate the box still open at its bottom side until the inner face of its lid rests against the layer of fruits, pressing the lid against the layer of fruits, turning the box, lifting the plate and thereby depositing the fruits on the inner side of the lid. Then the box is filled with fruits, the floor is nailed thereto and finally the box is turned in the right position.

One mode of carrying out the present invention is illustrated by way of example on the accompanying sheet of drawings in which

Figs. 1 and 2 show in plan view and side view respectively the plate of the device provided with excavations for the location of the top layer of fruits.

Figs. 3 and 4 show in plan view and side view respectively the counter plate co-operating with the plate provided with excavations.

Figs. 5 and 6 are similar views of the ejection plate and of the handle.

Fig. 7 is a view of the assembled device ready for use.

In the drawing, 1 designates the plate provided with excavations or depressions 2 for the reception of the top layer of fruits. Accorded to each excavation or depression is a bore 3, which terminates in a bore 4 of larger diameter at the backside of the plate (Fig. 2).

The counter plate 5 of the same size as the plate 1 is provided with bores 6 of the same diameter as the bores 4 and with smaller bores 7 of the same diameter as the bores 3 at the bottom side of said bores 6. Positioning pins 8 are arranged in the counter plate 5 which, in the assembled condition of the device, engage holes 9 provided in the plate 1. The ejectors preferably consist of metal and their collar 10 is adapted to slide in the enlarged bores 4 and 6 of the plates 1 and 5 respectively, while the stems 10^a and 10^b of each collar 10 operate in the small bores 3 and 7 respectively of said plates.

As shown in Fig. 7, the plates 1 and 5 are rigidly connected with one another by means of counter-sunk screws 11 in such a manner, that the enlarged bores of the two plates face one another and thereby form cylindric chambers in which operate the collars of the ejectors.

A bracket 12 used as handle is screwed at 13 to the bottom face of the plate 5. The plate 14, for operating the ejectors 10, 10^a, 10^b, is provided with four holes 15 for the passage of distancing members 16, which in convenient manner, for instance by means of wood-screws 17, are fixed to the plate 5 and at the bottom end are provided with heads or stops 18 against which rests the ejection-plate 14 in the position shown in Fig. 7. The ejection-plate also is provided with two slits 19, 20, through which pass the arms of the bracket 12.

The device operates in the following manner:

If the assembled device is in the position shown in Fig. 7, plums are put onto the top side of the device and deposited in the depressions 2 by shaking the device. Thereby the collars 10 of the ejectors pass into the bores 6 of the counter plate 5, so that the stems 10^a do not extend into the depressions 2 of the plate 1 (Fig. 7). Now the box, which is still open at its bottom side, is placed over the device until the inner face of the lid of the box rests on the plums orderly positioned in the depressions of the plate 1. By means of any convenient press, the lid of the box is pressed against the layer of

plums, so that known smooth surface is formed. Subsequently the box is removed from the press and turned. Now if, by means of the handle 12, the device 1, 5 is lifted out 5 of the box, all ejectors will be pushed inward simultaneously in the direction of the arrows (Fig. 7) in view of the weight of the ejection-plate 14 resting on the same, until the ejection-plate rests against the underside 10 of the plate 5 taking up the position shown in Fig. 7 in dash-dotted lines, while all ejectors take up the position of the first and fifth ejector illustrated in dash-dotted lines in Fig. 7, after they have ejected from the device the 15 whole layer of plums and deposited the same on the inner face of the lid of the box. Then the box, which is still open at its bottom side, is filled with fruits, the floor is nailed thereto and finally the box is turned in the right position.

20 I claim—

Device for forming the top layer of dried 25 fruits in boxes, comprising in combination a plate, depressions on the upper side of the plate for receiving the dried fruits, each depression communicating with a corresponding bore, passing through the plate, ejecting stems sliding axially in the said bores, enlargements in the bores, collars on the stems 30 guided in the enlargements, headed distancing members on the underside of the plate and an ejecting board sliding on said members for pushing the stems in the depressions and ejecting thereby the fruits.

35 In testimony whereof I affix my signature.
ERICH BERNFUS.
